UNITED STATES PATENT OFFICE.

EDWARD BALOD, OF NEW YORK, N. Y.

MARLINSPIKE.

Application filed October 25, 1924. Serial No. 745,941.

To all whom it may concern:

Be it known that I, EDWARD BALOD, a citizen of Latvia, and a resident of the city of New York, borough of Manhattan, in the county and State of New York, have invented a new and Improved Marlinspike, of which the following is a full, clear, and exact description.

This invention relates to improvements 10 in marlinspikes, and has particular reference to a spike employed in splicing wire cables and the like.

An object of the invention is to provide an improved spike of practical construction 15 the use of which will facilitate the operation of making a splice and drawing the strands taut.

The above and other objects will appear more clearly from the following detailed 20 description, when taken in connection with the accompanying drawing, which illustrates a preferred embodiment of the inventive idea.

In the drawing—

25 Figure 1 is an edge elevation of the spike constructed in accordance with the invention;

30 Figure 2 is a fragmentary longitudinal section on the line 2—2 of Figure 1, illustrating the manner in which a strand is engaged with the spike to draw the strand taut;

Figure 3 is an end elevation; and

35 Figure 4 is a section on the line 4—4 of Figure 1.

The spike which may be made of any suitable material is shown in the accompanying drawing as comprising the shank 5 of tapered formation and pointed at one end to facilitate its entrance between the strands of a cable or the like preparatory to splicing one of the strands. The intermediate portion of the shank 5 is preferably of substantially oval formation, as indicated in 45 Figure 4, and is provided along one edge thereof with a groove or channel 6 which, after the spike has been inserted between the strands of the cable, affords a space through which a strand may be passed during the splicing operation. By providing this groove it will be obvious that the usual difficulty of passing one strand between two other adjacent strands with no space between the latter strands and the spike is 50 obviated and consequently the splicing operation greatly facilitated.

At the large end of the shank the same has formed integrally therewith the transverse extending head or mallet 7 utilized to facilitate handling of the tool and preferably provided upon its outer face with an enlarged portion 8 which forms a striking point to be hit with a hammer or other implement in the event that difficulty is found in driving the shank between the strands of the cable. One end of the head 7 is bifurcated to form a tapered notch 9 extending longitudinally of the head and in which a strand 10 is capable of being wedged after said strand has been spliced 60 in order to draw said strand taut. In order to further hold the strand against slipping when being drawn taut the shank 5 is provided adjacent the head and in one face thereof with a transverse slot 11 capable 65 of receiving a portion of the strand 10 adjacent that portion extended through the notch 9 and the end of the strand is then engaged in the groove 6. The end of the head 7 opposite the notch 9 is provided with 70 a small rounded recess 12 for receiving the cable 13 so that end of the head will form a fulcrum about which the spike may be rocked in drawing the strand 10 taut. 75

It is sometimes desirable to bind or whip a splice and to this end one face of the head 7 is provided with a longitudinal groove 14 in which the spliced portion of the cable may be laid while a binding is being wound around said spliced portion. 80 After the binding has been started about the splice the free portion of the binding may be partially wound about the head and then by rotating the head about the splice said binding may be drawn tight. 95

What is claimed is:

1. A marlinspike including a tapered shank having a longitudinally extending groove therein for forming a space into which a strand may be inserted to extend 100 said strand between other adjacent strands when making a splice, said shank having a head formed at one end provided with a notch in one end thereof in which a spliced strand may be wedged, the other end of the 105 head being capable of engaging a cable and acting as a fulcrum for drawing the wedged strand taut.

2. A marlinspike including a tapered shank having a longitudinally extending 110 groove therein for forming a space into which a strand may be inserted to extend

said strand between other adjacent strands when making a splice, said shank having a head formed at one end provided with a notch in one end thereof in which a spliced strand may be wedged, the other end of the head being capable of engaging a cable and acting as a fulcrum for drawing the wedged strand taut, and the shank being provided adjacent said head with a transverse slot for receiving another portion of the spliced strand when the latter is being drawn taut.

3. A marlinspike including a shank having a head at one end provided in one end thereof with a tapered notch for receiving a portion of a spliced strand and said shank having a slot transverse to said notch and receiving another portion of said spliced strand, the end of the head opposite the

notch therein forming a fulcrum about which said spike is capable of being rocked to permit of said spliced strand being drawn taut.

4. A marlinspike including a shank having a head at one end provided in one end thereof with a tapered notch for receiving a portion of a spliced strand and said shank having a slot transverse to said notch and receiving another portion of said spliced strand, the end of the head opposite the notch therein forming a fulcrum about which said spike is capable of being rocked to permit of said spliced strand being drawn taut, one longitudinal face of said head being formed with a groove for receiving a splice when binding the same.

EDWARD BALOD.
